THE NORRIS PETERS CO., PHOTO-LITHO., WASHINGTON, D. C.

UNITED STATES PATENT OFFICE.

GEORGE A. COLTON, OF CHICAGO, ILLINOIS.

TRANSOM-LIFTER.

SPECIFICATION forming part of Letters Patent No. 470,780, dated March 15, 1892.

Application filed November 28, 1891, Serial No. 413,414. (No model.)

To all whom it may concern:

Be it known that I, GEORGE A. COLTON, a citizen of the United States, residing at Chicago, in the county of Cook and State of Illinois, have invented certain new and useful Improvements in Transom-Lifters, of which the following is a specification, reference being had therein to the accompanying drawings.

This invention pertains to transom-lifters, and more particularly to the guides for the rod and the base of the part holding the thumb-screw. It often happens that transom-lifters have but a narrow foundation to which to be fastened—for instance, a very narrow molding or beading at the side of the door-frame, so narrow sometimes that there is barely room for the screws to be put in, even though all in a line. Where there is sufficient width of molding or foundation, ordinarily the screws are put in one on either side of the upright rod, so that a line drawn through the screws would be at right angles to the rod. In order to fit all cases, a merchant is obliged to carry a stock of both right and left hand lifters—that is, some lifters in which the screws will all be on the right-hand side of the rod and other lifters in which the screws will be on the left-hand side of the rod.

The primary object of the present invention is to obviate the necessity of the carrying of a double stock and to permit of the adjustment of the screws either to the right or left, or at right angles to the rod. I construct the base, or rather the base and the guide, in two parts, so arranged as to be readily adjusted without removing the guide from the rod. The guide at the upper end of the rod may or may not be of the adjustable kind, as this may be slipped over the upper end of the rod and instantly made right or left, as may be desired; but inasmuch as the riveted stirrup or brace comes between this upper guide and the other one it will at once be seen how desirable it is to have the middle guide, as well as the foundation of the thumb-piece, reversible.

Other objects and advantages of the invention will hereinafter appear, and the novel features thereof will be specifically defined by the appended claims.

The invention is clearly illustrated in the

accompanying drawings, which, with the letters of reference marked thereon, form a part of this specification, and in which—

55

Figure 1 is a face view of my improvements applied to the rod. Fig. 2 is a central longitudinal section through the same, with the rod in elevation. Fig. 3 is a perspective view of one portion of the thumb-screw base. Fig. 60 4 is a like view of the other part. Fig. 5 is a plan of the guide-base. Fig. 6 is a like view of the guide. Fig. 7 is a central section through a modified form of guide and base.

Like letters of reference indicate like parts 65 throughout the several views in which they occur.

Referring now to the details of the drawings by letter, A designates the upright rod of a transom-lifter of known construction. B 70 is the stirrup for the brace-arm, the latter being indicated by dotted lines in Fig. 2 and designated by the letter C.

The novelty in the present invention resides in the making of the guide and its base 75 in such a manner as to permit of the adjustment before mentioned. This may be accomplished in various ways. I have illustrated several of them.

Referring to Figs. 3 and 4, will be seen the 80 lower guide, or that which also holds the thumb-screw which retains the rod, and consequently the transom in its adjusted position. It consists of the base or foundation D, having the apertured ears or lugs d for the 85 reception of the screws by which it is secured in position, the said lugs or ears being upon one side of the opening d', so that the screws will be in line. The opening d' is so constructed as to permit of the ready turning of 90 the portion E therein and yet prevent displacement. It is shown as being flanged, as seen at d², and the lower or inner end of the barrel or portion E is provided with a correspondingly-shaped flange e, as seen in Fig. 3, 95 to engage the same, as seen best in Fig. 2 in section, the barrel being provided with a passage-way e' for the passage of the upright rod A, and with a screw-threaded socket e² at right angles thereto for the reception of the 100 thumb-screw F, as seen in Fig. 2. The connection of the base and barrel may be otherwise formed—for instance, by making the parts beveling, as seen in Fig. 7. The center

guide G is of a similar construction, the base g being provided with the apertured ears or lugs g' , and the guide-ring G', having a base portion g^2 , working beneath a flange of the 5 base g, the upper face of the said base being provided with the diametrically - opposite notches g^3 to permit of the introduction of the ring portion from the rear, and then when turned at right angles to said notches or in 10 any position otherwise than coincident therewith the parts cannot be separated.

The mode of operation will be readily understood from the foregoing description when taken in connection with the annexed drawings, in which the different positions of the 15 parts are indicated by full and dotted lines.

Modifications in detail may be resorted to without departing from the spirit of the invention or sacrificing any of its advantages. 20 For instance, the aperture in the base may be rectangular and the base of the ring of a cor-

responding shape, as shown by dotted lines in Figs. 5 and 6; but the other forms are preferred, as the ring is most often turned after being placed upon the rod.

What I claim as new is—

1. A guide for a transom-lifter rod, consisting of a flanged base with apertured ears, a guiding portion rotatably connected with the base and having passage-way for the rod, and a socket for the reception of holding means for the rod, as set forth. 25

2. A rod-guide having a passage for a rod and a flanged termination formed for rotatable and removable connection with a base, as set forth. 30

In testimony whereof I affix my signature in presence of two witnesses.

GEORGE A. COLTON.
